Primary Examiner — Mary Ann Calabrese*Assistant Examiner* — Sloan Rozin(74) *Attorney, Agent, or Firm* — Cislo & Thomas, LLP(57) **CLAIM**

I claim the ornamental design for a table, as shown and described.

DESCRIPTION

FIG. 1 is a perspective view of my table;

FIG. 2 is a top view thereof;

FIG. 3 is a cross-sectional view of the cut-out designated by "3" in FIG. 2;

FIG. 4 is a bottom view of my table;

FIG. 5 is a right side view, the left side view (not shown) is a mirror image thereof;

FIG. 6 is a right end view, the left end view (not shown) is a mirror image thereof; and,

FIG. 7 is a close-up view of the area designated by "7" in FIG. 2.

The broken lines are for environmental purposes only and form no part of the claimed design.
